UNITED STATES PATENT OFFICE.

JACOB A. SCHOWALTER, OF NEAR NEWTON, KANSAS.

HEADED-GRAIN STACKER.

1,398,204.

Specification of Letters Patent. Patented Nov. 22, 1921.

Application filed October 20, 1920. Serial No. 418,148.

To all whom it may concern:

Be it known that I, JACOB A. SCHOWALTER, a citizen of the United States, residing near Newton, in the county of Harvey and State 5 of Kansas, have invented a new and useful Headed-Grain Stack, of which the following is a specification.

My present invention is a portable hoist, particularly for loading and unloading, 10 stacking and transferring headed grain, hay and fodder from barges, wagons, barns, and the like, or handling the material directly on the ground.

The principal object of the invention is to 15 produce a hoist of the above-mentioned type which is simple in construction, economical to produce and which is effective and efficient for its purposes.

One of the main features of the present 20 invention resides in the manner in which the derrick or hoist may be collapsed to enable it to be moved under telephone and telegraph wires and under shelter of the ordinary barn sheds.

25 The invention further resides in the sundry details of construction, combination and arrangement of parts hereinafter more fully described and pointed out in the appended claims.

30 In this specification and the annexed drawings, the invention is disclosed in the form in which it is considered to be the best, but the invention is not limited to such form because it is capable of being embodied 35 in other forms; and it is to be understood that in and by the claims following the description herein it is intended to cover the invention in whatever form it may embody within the scope thereof.

40 In the drawings:

Figure 1 is a perspective view to illustrate the hoist in accordance with the present invention.

Fig. 2 is a side elevation of the hoist 45 shown in Fig. 1, and illustrating in dotted lines the mast and boom collapsed.

Fig. 3 is a top plan view of the base socket 14 of the mast.

Fig. 4 is a top plan view of the movable 50 side wall of the socket.

Fig. 5 is a side elevation of the base socket.

Fig. 6 is a fragmentary detail view of the outer end of the boom.

Fig. 7 is a plan view of the bearing ring 55 for the turn table of the mast.

Fig. 8 is a plan view of the turn-table for the mast, and

Fig. 9 is a fragmentary detail view in perspective of the catch member between the turn-table 19 and bearing plate 17 when the mast is collapsed as shown in dotted lines Fig. 2.

Referring particularly to the drawings: the hoist comprises a portable base frame 34, to rest upon the ground and provided 65 with side runners *a*, having at its forward end traction wheels 28. Arranged over the forward end portion of the base frame is a circular bearing ring 17 supported in position by the uprights or standards 35 70 rising from the base frame and secured in downwardly depending channel sockets *b* on the ring. A mast 36 is provided for the hoist, and may be of any suitable construction, however in the present instance is 75 shown as constructed of side members *c* connected in spaced relation by spacing blocks *d* arranged at an intermediate point of the side members. Disposed between and secured to the lower ends of the side member 80 *c* of the mast is a spindle *e* which is normally received in a socket 14 secured to the forward end bar *f* of the base frame 34. The upper ends of the side member *c* of the mast converge and are held in substantially juxtaposition by the strap member 8 extending over the ends of the side members. The mast extends through an opening 19^a in a turn-table 19, which is secured to the mast intermediate its ends, as shown in Figs. 1, 90 7 and 8, by means of fastenings members 85 extending through flanges 19^b of the turn-table.

The turn-table 19 rests upon the ring 17 and rotatably supports the mast in conjunction with socket 14 against lateral movement. The mast is further supported in position against lateral movement by guy-cables 37 secured at one end to a swivel 7 on a spindle 38, projecting upwardly from 100 the strap 8 of the mast. The other ends of the guy-cables are secured in any suitable manner, such as by stakes, to the ground.

The mast is strengthened on its rear face 105 by a truss rod 12 secured at its upper end to a stirrup 11 arranged over the top end of the mast, and at its other end to a U shaped strap or stirrup 13, secured to the lower end portion of the mast considerably below the 110

turn-table 19. The truss rod 12 extends longitudinally of the mast on its rear face and has its ends connecting the stirrups 11 and 13. The end of the rod connecting the stirrup 13 extends loosely through the latter and has a nut 12^a adjustably threaded thereon. The spring 13^a is interposed between the stirrup and the nut, against which the nut binds, whereby a yieldable and adjustable connection between the rod and the stirrup 13 is provided for varying the tension on the rod. This rod 12 is spaced at an intermediate point in its length from the mast by a block or bridge 39. A boom 40 has one end secured to the mast between the side members *c* thereof, by means of a stationary pivot 41, located substantially midway between the top end of the mast and the turn-table 19.

20 The boom 40 consists of spaced and substantially parallel side members *g* maintained in spaced relation by a spacing member *h*. The outer end of the boom has a stirrup 3 extending around its end and side faces, as shown in Fig. 6, and secured to the boom by means of a bolt 6 extending therethrough.

25 The outer end of the boom 40 is raised and lowered by means of a cable 5 having one end secured to a yoke 4 connected to opposite ends of the bolt 6.

30 The cable 5 passes over pulley 10, secured to the upper end of the mast, and extends downwardly to a drum 21 secured to the lower end of the mast by means of brackets 20 and 22. The drum 21 is operated by the usual hand-crank 23, and may be held against unreeling rotation by any suitable means such as a pawl and ratchet.

35 40 A sling 42 is suspended from the outer end of the boom by means of a hoisting cable 43 having one end secured to the sling and passing between the block-and-tackle 44 suspended from hooks 1 disposed adjustably in notches 45 in the outer top surface of the boom, and the block and tackle 46 connected to the sling. From the block-and-tackle 44 the cable 43 passes to a pulley 47 journaled between the side members *c* of the mast and immediately below the boom pivot 41. From the pulley 47 the cable 43 passes downwardly to a pulley 48 secured to the end bar *f* of the base frame. The cable 43 may be operated either manually, or by draft or motive power in a manner which is well understood.

45 50 55 In order to permit the hoist to be knocked down with the outer end of the boom resting on the base frame 34 so that it may be stowed away, or to permit its passage under low trees and the like, the turn-table bearing ring 17 is formed on its front side with an arcuate opening 17^a substantially the width of the mast at that point, and the 60 65 socket 14 is provided with a removable side

wall 15, see Figs. 3, 4 and 5, thereby permitting the mast to be pivoted on the bearing ring 17 and moved to the position shown in dotted lines in Fig. 2. The wall 15 of the socket 14 is maintained in position by pins 16.

60 Of course, to accomplish this the mast is rotated 180° from its full line position shown in Figs. 1 and 2.

65 The turn-table 19 is provided with a laterally projecting lug 33 formed with a concaved face *x* adapted to engage in the stirrup 18 provided on the rear side of the bearing ring 17. The member 33 engaging in the member 18 prevents accidental displacement of the mast when in the position shown in dotted lines in Fig. 2, and also acts as a pivot upon which the mast will fulcrum when returning it to its upright or full-line position.

70 75 80 85 The wheels 28 of the hoisting rig are mounted on laterally extending supporting axles 29, as shown in Figs. 1 and 2, the axles being pivoted at points 30 in the front end bar *f* of the base frame to swing vertical. Levers 24 are arranged on each side of the base frame and pivotally secured thereto, as at 27, and overlie the axles 29. The other ends of the lever 24 are provided with fasteners 25 engageable in a complementary fastening member 26. It is therefore understood that when the fastening members 25 and 26 are engaged, the lever 24 will lie substantially parallel with the side members *a* of the base-frame, and bear upon the distal end of the axles 29, so as to raise the frame member above the ground and support its forward end on the wheels.

90 95 100 105 As will be clearly understood, with the parts in the position shown in Figs. 1 and 2, the entire base frame rests fully upon the ground in order to give a substantial and firm base for the hoisting rig when in operation.

110 From the foregoing, it will be clear that the present invention provides a hoisting rig which may be readily collapsed and of a light construction in order that it may be portaged, and at the same time providing one having great durability and economical 115 to produce.

Having thus described the invention, what is claimed is:

1. A hoist of the character described comprising a base, a mast mounted on the base frame for rotation about its longitudinal axis, and a supporting member mounted on the frame for laterally supporting the mast, said mast being pivotal on said lateral supporting member whereby the mast may be moved to a horizontal position.

2. A hoisting device of the character described, comprising a rotatable mast, means located intermediate the ends of the mast to laterally support the latter while being free

to rotate, said mast being pivotal on said support, whereby it may be moved to a horizontal position.

3. A hoist of the character described, comprising a portable rigging, a mast rotatably mounted on the rigging, means mounted on the rigging and engaging an intermediate portion of the mast to laterally support the same, said mast being pivotal on said supporting means whereby it may be moved to a horizontal position.

4. A hoist of the character described, comprising a rigging, a mast having a lateral flange intermediate its ends, means supported above the base of the rigging upon which the flange of the mast rests, means on the base of the rigging for maintaining the mast in vertical position, said mast being pivotal on said support whereby it may be moved to a horizontal position.

5. A hoist of the character described, comprising a supporting rigging, a ring supported by the rigging and arranged above the same, a mast extending through said ring and having its lower end received in a socket on the base of the rigging, a flange on said mast and resting on said ring whereby the mast is rotatably supported.

6. A hoist of the character described in claim 5, further characterized by the said ring having an arcuate opening therein, whereby the mast may be pivoted on the ring and moved out of the latter to a horizontal position.

35 7. A hoist of the character described in claims 5 and 6, further characterized by interengaging means on said mast and ring for preventing the accidental disengagement of the mast from the ring when in a horizontal position.

8. A hoist of the character described in claims 5 and 6 further characterized by the said socket having a removable part to permit the pivotal movement of the mast on the ring to a horizontal position.

9. A hoist of the character described, comprising a turn-table supported above the ground, a rotatably vertical mast extending through the turn-table and supported thereon and means engageable with the lower end of the mast to further maintain it in vertical position.

10. A hoist of the character described, in claim 9, further characterized by the end of the mast being disengageable from the means engaging its lower end and being horizontally pivotal at the turn-table to permit it to be moved to a horizontal position.

11. A hoist of the character described, comprising a mast, a boom secured to an intermediate portion of the mast on a stationary pivot, the outer end of the boom having a plurality of notches on its upper face, a hook member engageable over the outer end of the boom and adjustably engageable

in said notches, a block-and-tackle secured to the hook member, a stirrup extending underneath the lower face of the boom and side faces thereof, a yoke member straddling the boom, a bolt extending through the ends of the yoke member and said stirrup and boom, and a stay cable connected to the yoke member and to pulleys of the mast whereby the boom may be adjusted.

12. A hoist of the character described, comprising a rotatably supported mast, said mast comprising a pair of spaced side members converging at their upper ends and secured together by a U-shaped strap, a spindle extending upwardly from the strap, a swivel mounted on the spindle, guy cables extending from said swivel member, and a truss rod extending from end to end of the mast along its rear face and spaced therefrom at an intermediate point, the ends of said rod being secured to the end portions of the mast.

13. A hoist of the character described, comprising a base frame, a mast supported by the base frame, traction wheels on the base frame, and means between said frame and wheels permitting the frame to be lowered to the surface of the ground, whereby the weight of the hoist will be released from the wheels when in operation.

14. A hoist of the character described comprising a base frame, a mast supported by the base frame, stub axles laterally extending from said frame and pivoted thereon to move upwardly on said frame, supporting wheels on said axles, and releasable means for maintaining the axles against vertical movement, whereby the frame may be lowered to the ground when said releasable means are released.

15. A hoist comprising a frame, a mast on the frame, laterally extending stub axles pivoted on the frame to swing pivotally thereon, wheels on the axles, a lever pivoted to the frame and adapted to overlie said axles, releasable means for securing the levers in position to maintain the axles positioned to place the load of the hoist on the wheels, said levers engaging the axles and acting to lift the frame to place the load on the wheels.

16. In a hoist, a vertical mast, said mast comprising a pair of spaced members connected at their ends and at an intermediate portion thereof, stirrups secured to the end portions of the mast, a truss-rod arranged longitudinally along one face of the mast and having its ends connected to said stirrups and being adjustable with respect thereto, whereby the tension on the truss-rod may be varied, and a spacing block interposed between the mast and said rod at an intermediate portion thereof whereby the rod is spaced from the mast.

17. In a hoist, a vertical mast as described in claim 16 further characterized by the said

adjustment on said truss-rod being accomplished by having one end of the truss-rod extending through an opening in the said stirrups, a nut threaded on the extremity on 5 said end of said rod, and a resilient spring interposed between the nut and the stirrup against which spring the nut binds, whereby

a yieldable and adjustable connection between the truss-rod and the said stirrups is provided.

10

In testimony whereof I have hereunto set my hand.

JACOB A. SCHOWALTER.
